(57) **CLAIM**

The ornamental design for a footwear accessory, as shown and described.

DESCRIPTION

FIG. 1 is a perspective view illustrating the back, top and left side of a footwear accessory showing my new design; FIG. 2 is an elevation view of the front of the footwear accessory of FIG. 1;

FIG. 3 is an elevation view of the back of the footwear accessory of FIG. 1;

FIG. 4 is an elevation view of the right side of the footwear accessory of FIG. 1;

FIG. 5 is an elevation view of the left side of the footwear accessory of FIG. 1;

FIG. 6 is a plan view of the top of the footwear accessory of FIG. 1; and,

FIG. 7 is a plan view of the bottom of the footwear accessory of FIG. 1.

The elements shown in broken lines are for illustrating portions of the footwear accessory that form no part of the claimed design.

1 Claim, 7 Drawing Sheets
